ABSTRACT OF THE DISCLOSURE

Explosive compositions in powder form characterized by their suitability for use in wet situations comprising an explosive component, i.e., ammonium nitrate and/or potassium nitrate and/or ammonium chloride in association with explosive sensitizing ingredients and namely from 3 to 20 wt.-percent of at least one liquid nitric ester referred to the explosive mixture and 0.001 to 1 wt.-percent of a wetting agent referred to the water soluble components of the explosive mixture, the latter wetting agents rendering the water-soluble components of the explosive composition wettable by the nitric esters.

A process of waterproofing and sensitizing explosive compositions containing ammonium nitrate and/or potassium nitrate and/or ammonium chloride is also disclosed, the same comprising incorporating into such a composition at least one liquid nitric ester and a wetting agent.

This invention relates to explosive compositions which do not deteriorate in sensitiveness when used in wet situations.

It is well known that the ammonium nitrate blasting explosives and particularly ammonium nitrate powder explosives have a serious defect occasioned by the extreme water solubility and hygroscopicity of ammonium nitrate. This for instance leads to the rapid detonation of cartridges containing ammonium nitrate powder when the shots are laid in wet situations. The ammonium nitrate in the aforesaid kind of explosives has been replaced partially or entirely by equivalent amounts of sodium nitrate and ammonium chloride. The resulting explosive compositions, however, are still hygroscopic and quickly deteriorate in sensitiveness when used in wet situations.

It is in the prior art to waterproof the water soluble components of explosive mixtures in powder form, such as potassium nitrate, ammonium nitrate or ammonium chloride, by means of long-chained fatty acid salts and fatty amine salts, which are added in relatively small amounts as for example, 0.01 to 0.15% of the weight of the water-soluble explosive components. Larger quantities have a disadvantageous effect in that they have an adverse influence on the physical properties involved in detonation.

It is also in the prior art to add liquid nitric acid esters as sensitizers to explosive mixtures. The wetting action of nitric esters on the water-soluble explosive components, however, is relatively poor.

In accordance with the invention it has now been found that waterproof explosive compositions in powder form which are satisfactorily sensitive to detonation are obtained by combining as explosive ingredient at least one member selected from the group consisting of ammonium nitrate, alkali nitrate and ammonium chloride, at least one liquid explosive sensitizing ingredient, i.e., nitroglycerine, nitroglycol, diglycol dinitrate, dinitrochlorohydrin, nitro-pentaerythritol, said liquid nitric ester being used in an

amount of from 3 to 20% and preferably 5 to 15% referred to the explosive composition and from 0.001 to 1% and preferably 0.05 to 0.5% of the weight of the water soluble explosive ingredient of a wetting agent, the latter serving to render the water soluble explosive ingredient wettable by the nitric esters.

Surprisingly it has been found in accordance with the invention that the physical properties of the explosive mixture which are involved in detonation are considerably improved by the additives of the invention as a better distribution of the sensitizer is achieved by means of the wetting, along with the water-proofing of the water-soluble components of the explosive.

Instances of nitric esters suitable for use herein are, for example, the following: nitroglycerin, dinitrochlorohydrin, nitroglycol and diethylene glycol dinitrate.

The compounds which are suitable for use as wetting agents are characterized in that they contain one radical that is soluble in the nitric esters and one that is insoluble in the nitric esters and which is adherent to the water-soluble components of the explosive. Examples of radicals which are soluble in nitric esters are, for example, oxazolinyl, benzoylacetyl, naphthyl, naphthoxy, benzolazo and phenyl. Instances of radicals which are insoluble in nitric esters and which are adherent to the water-soluble components of the explosive are, for example, a paraffin radical, which may contain halogen or nitro group substituents, or a metal cation.

In the oxazoline derivatives (I) and (II):

35 R can represent one of the following:

—(CH₂)_x—CH₃
—NO₂
—(CH₂)_x—CH₃, —(CH₂)_x—(CH_y)—CH₃ or —(CH₂)_x—(CH_y)—CH₃
40 x can represent a whole number of from 3 to 18 and y a whole number of from 1 to 18.

Two oxazoline radicals can also be attached to an alkylene radical, as for example, in α,ω -bis-(2-phenyl-4-methyloxazolinyl-4)-dotriacantane:

Further examples of suitable wetting agents include the following: 2-naphthoxyacetic acid laurylamide, 2-naphthylstearylamine, sodium benzenesulfonate, sodium benzoate, the copper salts of benzoylacetone:

and the copper salts of benzolazonaphthene:

It is particularly preferred to use those wetting agents which simultaneously prevent deflagration, thereby achieving greater safety against firedamps in blasting operations.

The invention will be further illustrated by a detailed description in connection with the following specific examples of the practice of it. The examples are, however, in no wise to be construed as limiting the scope of the invention.

Example 1

(a) An explosive mixture consisting of:

Oxazoline wax (a mixture of 8 parts by weight of α,ω -bis-(2-phenyl-4-methoxyazolinyl-4)-dotriaccontane and 2 parts by weight of α -(2-phenyl-4-methoxyazolinyl-4)-tetratriaccontane) -----	10
Ammonium chloride -----	1509
Potassium nitrate -----	2630
Hydrate of alumina -----	20
Blasting gelatin consisting of a mixture of 60% by weight of nitroglycerin and 40% of nitro-glycol -----	355
Galactomannitol -----	30

(b) An explosive mixture having the same composition as under (a), but with the difference that 10 g. of Vaseline (petroleum jelly) is used in place of the oxazoline wax, and

(c) An explosive mixture as under (a), but without the blasting gelatin, were prepared and subjected to a series of explosive test procedures.

The preparation of the explosive mixture was carried out in the following manner:

10 g. of oxazoline wax or Vaseline (petroleum jelly) were mixed with 100 g. of ammonium chloride and then this mixture admixed with the remaining components. The axazoline wax was wetted by the blasting gelatin, but not by water. The Vaseline, on the other hand, was wetted neither by the blasting gelatin nor by water. The following table shows the test data obtained:

TABLE 1

Explosive Mixture	a	b	c
Cartridge density in g./ccm.	1.17	1.17	1.28
Cartridge diameter in mm.	30	30	30
Compression according to Hess in mm.	4.1	3.1	-----
Water resistance in cm./min.	1 50/60+ ¹	2 50/30-	-----
One drop of water remains on substance for minutes	50	0	0

The cartridge is not paraffined.

¹ 50/60+-- Indicates that 4 cartridges were still detonatable after having lain 50 cm. underwater for 60 minutes.

² 50/30-- Indicates that 4 cartridges were no longer detonatable after having lain underwater at a depth of 50 cm. for 30 minutes.

Example 2

(a) An explosive mixture consisting of:

Oxazoline wax (as in Example 1) -----	1.6
Fatty amine salts of linseed oil fatty acids (mixture of 35 parts by weight of stearylamine, 17.5 parts coconut fatty amine, 40.5 parts linseed oil fatty acid and 7 parts ammonium nitrate) -----	55
Ammonium chloride 100% (grain size under 0.1 mm.) -----	2.4
Potassium nitrate 80% (grain size under 0.1 mm.) -----	3236.7
Hydrate of alumina -----	12
Blasting gelatin (as in Example 1) -----	320
Collodion cotton -----	0.4
Finely powdered silicic acid -----	0.4
Galactomannitol -----	38

(b) An explosive mixture as under (a), but without oxazoline wax were prepared and subjected to explosive test procedures.

The preparation of the explosive mixture was carried out as follows: The oxazoline wax and fatty amine salts were melted together. The resulting mixture was then wetted with blasting gelatin. The mixture thus obtained

was thereafter mixed with ammonium chloride and potassium nitrate and finally with the remaining components.

The following table sets out the results which were obtained.

TABLE 2

G.	Explosive Mixture	a	b
10	Cartridge density in g./ccm.	1.12	1.11
10	Compression according to Hess in mm.	4.8	4.6
10	Detonation transmission on sand in cm.	15+ 20+ 50+	10+ 40+ 60+
10	Deflagration test carried out in the Bichl bomb ²	(3)	(4)

The cartridge was not paraffined.

¹ + Represents detonation transmission.

— Represents no detonation transmission.

² 2½ cartridges (approx. 270 g.) of Wetter-Carbonit B were brought to detonation on the bottom of the Bichl bomb. A perforated plate was placed on the bomb, and the explosive being evaluated (a) and the one being used for comparison (b) were placed on the plate at a distance of approximately 10 cm. from one another.

³ No deflagration; cartridge intact, ammonium chloride and potassium nitrate crystals still visible.

⁴ Deflagration; cartridge deformed by chemical reaction. No ammonium chloride or potassium nitrate crystals visible.

Example 3

(a) An explosive was prepared as follows from:

G.	Explosive Mixture	a	b
30	Copper acetate · 1H ₂ O	10	10
30	Ammonium chloride	1360	1360
30	Potassium nitrate	2620	2620
30	Blasting gelatin (as in Example 1)	400	400
35	Benzoyl acetone	10	10
35	Collodion cotton	0.45	0.45
35	Hydrate of alumina	20	20
35	Wood meal	20	20
	Galactomannitol	60	60

(1) Copper acetate was dissolved in water and sprayed onto ammonium chloride and potassium nitrate.

(2) Benzoyl acetone and collodion cotton were dissolved in blasting gelatin.

Preparations 1 and 2 were mixed together and thereafter the remaining components added and the mixing continued. Benzoyl acetone reacted with the copper acetate to form a salt which was wet by blasting gelatin, but not by water.

(b) A comparative explosive was prepared as above, but without benzoyl acetone and copper acetate.

The results obtained in testing of the explosives are summed up in the following table.

50

TABLE 3

G.	Explosive Mixture	a	b
55	Cartridge density in g./ccm.	1.31	1.29
55	Cartridge diam. in mm.	30	30
55	Compression according to Hess in mm.	4.3	4.0
55	Water resistance in cm./min.	100/60+ ¹	50/20-

Cartridge was not paraffined.

¹ 100/60+-- Designates that 4 cartridges were still detonatable after having lain under water at a depth of 100 cm. for 60 minutes.

50/20-- Means that 4 cartridges were no longer detonatable after having lain 50 cm. under water for 20 minutes.

Example 4

(a) An explosive was prepared from:

G.	Explosive Mixture	a	b
1.6	Copper acetate · H ₂ O	17	17
1.6	Ammonium chloride	1360	1360
1.6	Potassium nitrate	2620	2620
1.6	Blasting gelatin (as in Example 1)	400	400
1.6	1-benzolazo-naphthol-2	10	10
1.6	Acetone	15	15
1.6	Collodion cotton	0.45	0.45
1.6	Wood meal	20	20
1.6	Hydrate of alumina	20	20
1.6	Galactomannitol	60	60

Ammonium chloride and potassium nitrate were treated with an aqueous solution of copper tetramine acetate solution. Benzolazonaphthol was dissolved in acetone together with blasting gelatin. The mixing together of the two compositions produced the copper salt of benzolazonaphthol. This salt was wet by blasting gelatin, but not be water.

(b) An explosive was then prepared without benzolazonaphthol and copper acetate, for use as a comparison explosive.

The test data which were obtained with these explosives are set out in the following table.

TABLE 4

Explosive Mixture	a	b
Cartridge density in g./ccm.	1.24	1.29
Cartridge diam. in mm.	30	30
Compression according to Hess in mm.	6.0	3.9
Water resistance in cm./min.	100/60+	50/20-

The cartridge was not paraffined.

100/60+ Designates that 4 cartridges were still detonatable after lying under water at a depth of 100 cm. for 60 minutes.

50/20- Designates that 4 cartridges were no longer detonatable after lying 50 cm. under water for 20 minutes.

Example 5

(a) An explosive mixture was prepared by mixing together the following:

	G.
Ground ammonium nitrate	3132
Oxazoline wax (as in Example 1)	16
Dinitrotoluene	80
Trinitrotoluene	480
Wood meal	80
Coloring components	8
Blasting gelatin (as in Example 1)	240

(b) A comparison explosive was prepared which contained 0.40% paraffin in place of the wetting agent. The data which appears in the following table was obtained when these explosives were subjected to testing:

TABLE 5

Explosive Mixture	a	b
Cartridge in mm.	30	30
Water resistance in cm./min.: 4 cartridges were kept 50 cm. under water for 60 minutes.	Detonation transmission still occurred at a cartridge distance of 15 cm.	Detonation transmission still occurred at a cartridge distance of 5 cm., but not at 6 cm.
4 cartridges were kept 100 cm. under water for 60 minutes.	Detonation transmission still occurred at a cartridge distance of 10 cm.	Detonation transmission ceased beyond a cartridge distance of 6 cm.

The cartridge was not paraffined.

Example 6

(a) An explosive mixture as set out in Example 5 was prepared but the oxazoline wax was replaced by a mixture of oxazoline wax and fatty amine salts (as in Example 2) in a weight ratio of 3:2. This mixture was also wet by blasting gelatin.

(b) An explosive was prepared for use as a comparison explosive and contained 0.40 wt.-percent paraffin instead of the wetting agent. In the following table the test data which was obtained with these explosives is set out.

55 (a) An explosive was made from the following components:

	G.
Sodium benzoate	4
Potassium nitrate	2326.7
Ammonium chloride	1240
Hydrate of alumina	100
Finely powdered silicic acid	1
Blasting gelatin	350
Galactomannitol	38

Example 8

(a) An explosive was made from the following components:

Explosive Mixture	a	b
Cartridges in mm.	30	30
Water resistance in cm./min.: 4 cartridges were held under water at a depth of 50 cm. for 60 min.	Detonation transmission still occurred afterward at 12 cm. spacing.	Detonation transmission still occurred afterward at 5 cm. spacing, but not at 6 cm. spacing.
4 cartridges were held under 100 cm. of water for 60 min.	Detonation transmission still occurred at 10 cm. spacing.	Detonation transmission no longer occurred thereafter at a spacing of 0 cm.

The cartridge was not paraffined.

(a) An explosive was prepared using the following components:

	G.
Sodium benzene sulfonate	4
Ammonium chloride	20
Potassium nitrate 70% (grain size under 0.1 mm.)	2327
Ammonium chloride 65% (grain size under 0.1 mm.)	1220
Hydrate of alumina	100
Finely powdered silicic acid	1
Blasting gelatin	350
Galactomannitol	38

The explosive was prepared in the following manner: 4 g. of sodium benzene sulfonate were mixed together with 20 g. ammonium chloride, and this mixture was then mixed with the remaining components.

(b) An explosive was prepared for use as a comparison but contained no sodium benzene sulfonate.

The test data obtained using these two explosives is summarized in the following table:

TABLE 7

Explosive Mixture	a	b
Cartridge density in g./ccm.	1.10	1.12
Compression according to Hess in mm.	3.1	2.3
Water resistance in cm./min.	150/2 60	10/3 30

The cartridge was not paraffined.

¹ The first figure represents the depth of water to which the cartridge is submerged, and the second the time in minutes.

² Still detonates if the cartridges were adjacent one another.

³ No longer detonates thereafter even if the cartridges were placed adjacent one another.

The explosive corresponding to the above was prepared as follows: the sodium benzoate was mixed with ammonium chloride and the resulting mixture was then combined with the rest of the components.

(b) An explosive was prepared for use as a comparison and contained no sodium benzoate. The test data which was obtained with these explosives is set out in the following table:

TABLE 8

Explosive Mixture	a	b
Cartridge density in g./cm. ³	1.15	1.12
Compression according to Hess in mm.	2.7	2.3
Water resistance in cm./min.	1/50/60	2/10/30

¹ Still detonates if the cartridges were adjacent one another.

² No longer detonates even if cartridges were adjacent one another.

We claim:

1. A blasting explosive composition comprising:

(1) a water soluble explosive component comprising at least one member selected from the group consisting of ammonium nitrate, alkali nitrate and ammonium chloride,

(2) 3 to 20 wt.-percent referred to the total explosive composition of a liquid nitric ester, and

(3) 0.001 to 1 wt.-percent referred to said water-soluble component comprising a compound containing one radical which is soluble in said nitric ester and one radical which is insoluble in said nitric ester and which is adherent to said explosive component,

said wetting agent rendering said explosive component wettable by said liquid nitric ester.

2. A blasting explosive composition according to claim 1 wherein said liquid nitric ester is present in an amount of from 5 to 15 wt.-percent referred to the explosive composition.

3. A blasting explosive composition according to claim 1 wherein said liquid nitric ester is at least one member selected from the group consisting of nitroglycerin, dinitrochlorohydrin, nitroglycol and diethylene glycol dinitrate.

4. A blasting explosive composition according to claim 1 wherein said wetting agent is present in an amount of 0.05 to 0.5 wt.-percent referred to the explosive component.

5. A blasting explosive composition according to claim 1 wherein said wetting agent is a member selected from the group consisting of

wherein R is a member of the group consisting of $-(\text{CH}_2)_x-\text{CH}_3$,

wherein x is a whole number of from 3 to 18 and y is a whole number of from 1 to 18,

wherein p has a value of from 2 to 40, 2-naphthoxyacetic acid laurylamide, 2-naphthylstearylamine, sodium benzene-sulfonate, sodium benzoate,

and

6. A blasting explosive composition according to claim 1 additionally containing at least one member selected from the group consisting of wood meal, urea, guanidine nitrate, argillaceous earths, china clay, wheat flour, water-soluble carboxymethyl cellulose, galactomannitol copper acetate.

15 7. A blasting explosive composition according to claim 1 comprising:

G.

Oxazoline wax (a mixture of 8 parts by weight of α - ω - bis - (2 - phenyl - 4 - methyloxazolinyl-4) - dotriacantane and 2 parts by weight of α - (2 - phenyl - 4 - methyloxazolinyl - 4) - tetratriacantane) ----- 10

Ammonium chloride ----- 1509

Potassium nitrate ----- 2630

25 Hydrate of alumina ----- 20

Blasting gelatin consisting of a mixture of 60% by weight of nitroglycerin and 40% of nitroglycol ----- 355

Galactomannitol ----- 30

30 8. A blasting explosive composition according to claim 1 comprising:

G.

Oxazoline wax ----- 1.6

35 Fatty amine salts of linseed oil fatty acids (mixture of 35 parts by weight of stearylamine, 17.5 parts coconut fatty amine, 40.5 parts linseed oil fatty acid and 7 parts ammonium nitrate) ----- 2.4

Ammonium chloride 100% (grain size under 0.1 mm) ----- 1240

40 Potassium nitrate 80% (grain size under 0.1 mm) ----- 2326.7

Hydrate of alumina ----- 12

Blasting gelatin (60% by weight nitroglycerin and 40% by weight nitroglycol) ----- 320

45 Collodion cotton ----- 0.4

Finely powdered silicic acid ----- 0.4

Galactomannitol ----- 38

50 9. A blasting explosive composition according to claim 1 comprising:

G.

Copper acetate $\cdot 1\text{H}_2\text{O}$ ----- 10

Ammonium chloride ----- 1360

Potassium nitrate ----- 2620

55 Blasting gelatin (60% by weight of nitroglycerin and 40% by weight nitroglycol) ----- 400

Benzoyl acetone ----- 10

Collodion cotton ----- 0.45

Hydrate of alumina ----- 20

60 Wood meal ----- 20

Galactomannitol ----- 60

65 10. A blasting explosive composition according to claim 1 comprising:

G.

Copper acetate $\cdot 1\text{H}_2\text{O}$ ----- 17

Ammonium chloride ----- 1360

Potassium nitrate ----- 2620

Blasting gelatin (60% by weight of nitroglycerin and 40% by weight nitroglycol) ----- 400

70 1-benzolazo-naphthol-2 ----- 10

Acetone ----- 15

Collodion cotton ----- 0.45

Hydrate of alumina ----- 20

Wood meal ----- 20

75 Galactomannitol ----- 60

11. A blasting explosive composition according to claim 1 comprising:

	G.	
Ground ammonium nitrate	3132	
Oxazoline wax (4:1 mixture of α,ω -bis-(2-phenyl-4-methyloxazolyl-4) - dotriaccontane and α -(2-phenyl - 4 - methyloxazolyl - 4) - tetratriacontane)	5	
Dinitrotoluene	16	
Trinitrotoluene	80	
Wood meal	480	10
Coloring components	80	
Blasting gelatin (60% by weight nitroglycerin and 40% by weight nitroglycol)	240	15

12. A blasting explosive composition according to claim 1 comprising:

	G.	
Sodium benzene sulfonate	4	20
Ammonium chloride		20
Potassium nitrate 70% (grain size under 0.1 mm.)	2327	
Ammonium chloride 65% (grain size under 0.1 mm.)	1220	
Hydrate of alumina	100	25
Finely powdered silicic acid	1	
Blasting gelatin (60% by weight nitroglycerin and 40% by weight nitroglycol)	350	
Galactomannitol	38	30

13. A blasting explosive composition according to claim 1 comprising:

	G.	
Sodium benzoate	4	35
Potassium nitrate		2326.7
Ammonium chloride		1240
Hydrate of alumina	100	

	G.
Finely powdered silicic acid	1
Blasting gelatin (60% by weight nitroglycerin and 40% by weight nitroglycol)	350
Galactomannitol	38

14. A method for preparing a blasting explosive which is non-hygroscopic and does not deteriorate in sensitiveness when used in wet situations comprising forming a mixture of

- (1) a water soluble explosive component comprising at least one member selected from the group consisting of ammonium nitrate, alkali nitrate and ammonium chloride,
- (2) 3 to 20 wt.-percent referred to the total explosive composition of a liquid nitric ester, and
- (3) 0.001 to 1 wt.-percent referred to said water-soluble component comprising a compound containing one radical which is soluble in said nitric ester and one radical which is insoluble in said nitric ester and which is adherent to said explosive component, said wetting agent rendering said explosive component wettable by said liquid nitric ester.
